UNITED STATES PATENT OFFICE.

FRIEDERICH MÜLLER, OF HARTFORD, CONNECTICUT, ASSIGNOR TO PRATT & WHITNEY COMPANY, OF HARTFORD, CONNECTICUT, A CORPORATION OF NEW JERSEY.

RELIEVING-LATHE.

1,299,208.

Specification of Letters Patent.

Patented Apr. 1, 1919.

Application filed January 27, 1917. Serial No. 144,924.

To all whom it may concern:

Be it known that I, FRIEDERICH MÜLLER, a citizen of the United States, residing at Hartford, in the county of Hartford and State of Connecticut, have invented certain new and useful Improvements in Relieving-Lathes, of which the following is a specification.

The invention relates particularly to lathes for relieving counterbores and other rotary metal working cutters requiring endwise relief. However, the machine is not limited for use upon cutters of the kind mentioned and can be used for practically all classes of work requiring longitudinal relieving movements of the cutting tool. For the sake of convenience the term "cutters" is used throughout this specification, but it will be understood that the term is intended to include not only rotary metal working tools but also any other articles for which endwise relief is required.

One of the objects of the invention is to provide an improved form of mounting for the tool carrying slide and the tailstock.

Another object of the invention is to provide an improved form of automatic feeding means whereby the cutting tool can be advanced so as to take a fresh chip upon each revolution of the cutter.

Other objects of the invention will be apparent from the following specification and the claims.

In the accompanying drawings I have shown a machine similar in many respects to that shown in my copending application for relieving lathes, Serial No. 139,838, filed December 30, 1916. A machine embodying my present invention is much simpler than that shown in the said copending application and is therefore preferable when the circumstances are such that it is only necessary to use the machine for cutters requiring endwise relief.

The construction shown in the drawings is the one which I now deem preferable, but it will be understood that the drawings and the description are intended to be merely illustrative and are not intended to define or limit the scope of the invention, the accompanying claims being relied upon for that purpose.

Of the drawings:

Figure 1 is a side view of a machine embodying the invention, some of the parts be-

ing shown in elevation and others in vertical section.

Fig. 2 is a plan view, some of the parts being removed for the sake of clearness.

Fig. 3 is an end view, taken from the left 60 as viewed in Figs. 1 and 2.

Fig. 4 is an end view taken from the right as viewed in Figs. 1 and 2, some of the parts being shown in section.

Fig. 5 is a transverse vertical sectional 65 view taken along the line 5—5 of Fig. 2.

Fig. 6 is a transverse vertical sectional view taken along the line 6—6 of Fig. 2.

Fig. 7 is a fragmentary sectional view taken along the line 7 of Fig. 2. 70

Referring to the drawings, 1 represents the main base or bed upon which the other parts of the machine are mounted. Means are provided for holding and rotating a cutter to be relieved, this means preferably comprising a headstock 2 and a tailstock 3, each provided with a center. It will be understood, however, that so far as certain features of the invention are concerned I do not limit myself to the particular construction 75 shown, and that the cutter may, if preferred, be otherwise held, as for instance by a chuck or collet.

The headstock is provided with a frame casting 4 rigidly secured to the bed. This 80 casting is provided with suitable bearings 5 and 6 in which there is rotatably mounted a live spindle 7 which preferably carries a center 8 and a face plate 9.

Loosely mounted on the spindle 7 are two 90 worm wheels 10 and 11. Preferably, as indicated in Fig. 2, the teeth of the worm wheel 10 are adapted to mesh with a double-threaded worm, and the teeth of the worm wheel 11 are adapted to mesh with a single-threaded worm. Extending transversely of the headstock and mounted in suitable bearings in the casting 4, is a drive shaft 12 provided at its rear end with a driving means, here shown in the form of a set of cone belt 100 pulleys 13. Secured on the drive shaft 12, preferably adjacent the belt pulleys, is a pinion 14 which meshes with pinions 15 and 16 mounted respectively on suitably mounted transverse shafts 17 and 18. Mounted re- 105 spectively on the shafts 17 and 18 are worms 19 and 20 which mesh respectively with the aforesaid worm wheels 10 and 11. When the worm wheels are constructed as already described, the worm 19 is provided with 110

double threads and the worm 20 with a single thread. It will be seen that the construction is such that when the worms 19 and 20 are rotated the worm wheels will be given different rotative speeds, the wheel 10 in this case having a speed considerably in excess of that of the wheel 11.

Splined to the spindle between the worm wheels 10 and 11 is a clutch element 21 having teeth at each side adapted respectively to mesh with similar teeth formed on the worm wheels. It will be seen that by means of this clutch element either of the worm wheels can be operatively connected with the spindle.

For moving the clutch element 21 longitudinally of the spindle, there is provided an oscillatory lever 22 provided with pins or projections 23, 23 fitting in a circumferential groove in the clutch element. The lever 22 is secured to a transverse rock shaft 24 provided with an operating lever 25. It will be seen that by means of the lever 25 the clutch element 21 can be controlled so as to be maintained in neutral position as shown in Fig. 1, or moved into engagement with either of the worm wheels 10 or 11. The lever 25 is provided with a spring-pressed pin 26 adapted to enter suitable holes in the casting 4 and thus lock the lever and the clutch element in the desired position.

Mounted on the bed 1 for longitudinal movement is a tool carrying slide 27, which will be referred to again hereinafter. The tailstock 3 is mounted on the bed in such a way as not to interfere in any way with the said slide 27. As shown in Fig. 4, the tailstock is carried by ways positioned at the sides of the slide, the arrangement being such that the slide can move longitudinally entirely independently of the tailstock and that the tailstock can be adjusted longitudinally entirely independently of the slide.

Because of the peculiar mounting of the tailstock it is not possible to make use of devices of the usual sort for locking or clamping it in place. I provide devices at the sides of the tailstock, these devices being adapted to engage the bed and being preferably provided with means for simultaneously actuating them. As shown, the two clamping devices are in the form of levers 28 and 29 pivoted respectively to ears formed on the sides of the main tailstock casting. These levers are formed with inner projections adapted to engage downward exposed inclined surfaces at the sides of the bed. For forcing the two levers toward each other into engagement with the bed, I provide a threaded rod 30 pivoted at 31 to the lever 28 and extending through an aperture in the lever 29. A nut 32 engages the rod, this nut preferably constituting the hub of a hand wheel 33. Interposed between the nut or hub 32 and the

lever 29 is a washer 34 having a horizontal projection adapted to provide a rocking contact with the lever. Preferably a spring 35 engaging a collar 36 is provided for separating the two levers when the nut or hub 32 is turned to permit such separation.

It will be seen that the construction described constitutes a differential means for effecting simultaneous uniform clamping actions at both sides of the tailstock. Each lever serves as an abutment for the application of pressure to the other.

As concerns the other parts of the tailstock, any usual or preferred construction can be used. I have shown a sliding sleeve 37 adapted to be moved longitudinally under the control of a screw 38 and a hand wheel 39. By means of a clamp 40 the sleeve can be held in adjusted position. Mounted in the sleeve 37 is a center 41.

It will be seen that by suitably positioning the tailstock on the bed and by them adjusting the center 41 by means of the screw 38 and hand wheel 39, a cutter or other article to be relieved can be secured in the usual way between the two centers 8 and 41; and the cutter can be connected to the live spindle by means of the face plate 9 to be rotated in the usual way.

As already stated, it may in some cases be preferable to mount the cutter entirely on the live spindle, and for this purpose a collet mechanism such as shown in Fig. 1 may be provided. The spindle 7 is hollow and rotatably mounted therein is a sleeve or bushing 42 controllable by a hand wheel 43. The sleeve 42 has threaded engagement with a collet 44. By turning the hand wheel and the sleeve in one direction or the other the collet can be drawn inward and closed or moved outward and permitted to open. The shank of a cutter to be relieved can be inserted in the collet and the cutter can thus be held and rotated independently of the tailstock. A rod 45 adjustably mounted in the sleeve 42 serves as an abutment to limit the inward movement of the cutter shank. When a center is used as shown, it can be mounted in the collet. When the cutter is mounted entirely on the live spindle, it is possible, if desired, to entirely remove the tailstock.

The cutting tool must be so held and supported that it can be moved toward and from the cutter to be relieved in timed relation to the rotation thereof. The tool must make as many movements forward and backward during each rotation as the cutter has teeth. For supporting the tool the aforesaid longitudinal movable slide 27 is provided. As shown, the bed 1 is provided with rabbets in which the slide 27 fits. The slide is held in place by means of gib 46 and 47.

Connected with the slide 27 for normal

movement in unison therewith, is a device 48 to which power is applied for actuating the slide. Preferably the device 48 is provided on its lower side with a transverse slot 5 having vertical parallel surfaces 49 extending at right angles to the lines of reciprocation of the slide 27. Pivoted on the bed at 50 is a lever 51 having two arms, one of which engages the actuating device 48 and the other of which is engaged by a suitable cam member 52. The cam member 52 is mounted on a vertical shaft 53, preferably being directly connected to a worm wheel 54 also mounted on said shaft. The shaft 54 is rotatable in suitable bearings formed in a housing 55 secured to the bed.

The cam member 52 is provided in its top surface with a cam groove 56 into which fits a pin or roller on one arm of the lever 51. The groove is preferably of the form shown in Fig. 2, being adapted to move the lever slowly in one direction and rapidly in the other. The lever 51 is adjustable so as to vary the amount of movement which the cam transmits to the tool-carrying slide. Preferably this adjustment is effected by changing the effective length of one arm of the lever, and as shown, this arm of the lever is constructed with two telescopically engaging parts. At the sides of the body part of the lever are two slidable plates 57, 57 formed with oppositely disposed thickened portions 58, 58 each with a surface in the form of a section of a cylinder, these two cylindrical surfaces having a common center. The surfaces of the enlargements 58, 58 fit between the surfaces 49, 49 of the actuating device 48, and as the surfaces of the parts 58, 58 are cylindrical, the engagement with the surfaces 49, 49 is maintained notwithstanding any angular movement. The two plates 57, 57 are secured to a block 59 which is centrally recessed to receive an extension 60 on the body part of the lever. An adjusting screw 61 extends through an aperture in the block and is held against longitudinal movement with respect thereto. The inner end of the screw extends into a threaded aperture in the said extension 60. The outer end of the screw is squared to receive a wrench and by turning the screw the block 59 together with the plates 57, 57 can be moved so as to bring the center of the cylindrical surfaces 58, 58 toward or away from the pivotal center of the lever. Preferably at the extreme inner position the center of the cylindrical surfaces coincides with the pivotal center, and no movement of the actuating device or the slide takes place as the lever is oscillated. As the screw is turned to move the center of the cylindrical surfaces outward, the movement of the actuating device and slide is gradually started and this movement is increased as the effective length of the lever is increased. In

this way the extent of movement of the tool slide can be varied from zero to maximum. The screw 61 can be clamped by means of the screw 62.

As already stated, the cam 56 is in the form of a groove, thus making it possible for the cam to positively move the lever in each direction, the construction being distinguished in this present respect from other constructions in which the cam is effective in one direction only, reliance being placed upon a spring for effecting movement in the other direction. While, as stated, the cam acts positively in both directions, I nevertheless prefer to provide a spring for assisting the cam in effecting the short rapid return movement of the slide. By means of the spring I avoid excessive strain on the lever, the cam, and the several power transmitting parts. As illustrated, there is provided a lever 63 horizontally pivoted to the bed 1 and at its upper end engaging a lug 64 depending from the actuating device 48. Pivottally connected to the lower end of the lever 63 is a rod 65 which extends through an aperture in a cross member 66 extending from one side to the other of the bed 1. A coil spring 67 surrounds the rod 66, one end of the spring abutting against the said cross member and the other end being engaged by a nut 68 on the rod. By means of the rod and the lever the force of the spring is transmitted to the actuating devices 48 and the tool carrying slide 27, tending to move these parts backward, thus assisting the cam in one direction.

For rotating the cam member 52 and the worm wheel 54 there is provided a worm 69. The worm is mounted on a transverse shaft 70 suitably mounted in the bed of the machine. Power to rotate the shaft 70 is transmitted from the aforesaid drive shaft 12 by means of a series of gears, these gears being interchangeable so as to provide for the driving of the shaft 70 at different speeds. As shown, the shaft 12 is provided at its forward end with a pinion 71 which meshes with a gear 72 mounted on a stud shaft 73. Rigidly connected with the gear 72 is a pinion 74 which meshes with an idler gear 75 mounted on a stud 76 which is slidable in a bracket 77 secured to the bed. This gear 75 meshes with a second idler gear 78 which is mounted on a stud 79 secured to a bracket 80 mounted for swinging movement on the shaft 70. This bracket can be locked by means of a bolt 81. The gear 78 meshes with a gear 79 on the shaft 70. It will be seen that when the shaft 12 is rotated the shaft 70 will also be rotated but at a greatly reduced speed. If a different speed is required for the shaft 70, this can be obtained by removing the gears 71, 72 and 74 and substituting other gears of different diameters. It will be noted that the idler gears 130

75 and 78 are adjustable so that proper meshing with the differently diametered gears is effected.

As has already been stated, it is necessary 5 for the cutting tool to make one forward and backward movement for each tooth of the cutter to be relieved. It is therefore necessary that for each revolution of the live spindle the cam 56 be given as many rotations as the cutter has teeth. By using gears of the proper sizes the number of rotations of the cam for each rotation of the live spindle can be varied as desired, and a further variation can be obtained by connecting one or the other of the gears 10 or 11 10 with the live spindle, thus varying the speed of the spindle with respect to the speed of the drive shaft 12. By means of this two-speed worm and wheel drive mechanism for 15 the spindle, I am enabled to greatly increase the range of the machine without providing an unduly large number of interchangeable gears.

As already stated, the cutting tool can 20 be mounted on the slide 27 in any suitable manner. I prefer a tool-holding and supporting means which comprises a plate 82 secured to the slide by means of bolts 83. The slide is provided with a T-slot 84 into 25 which the bolts fit, thus making it possible for the plate 82 to be adjusted along the slide and locked in adjusted position. Mounted on the plate 82 is a slide 85 movable at right angles to the slide 27 and 30 adapted to be controlled by the screw 86 and the hand wheel 87. Carried by the slide 85 are studs 88, 88, and a suitable tool clamp holding a tool 89 may be secured in place by either of the studs as required.

40 The actuating device 48 has been described as normally movable in unison with the tool carrying slide 27. The two elements are connected by a rotatable screw 90 which has threaded engagement with an element 45 91 of the slide 27. The inner end of the screw extends through an aperture in the actuating device 48 and is held against longitudinal movement with respect to the said device by means of lock nuts at 92. Mounted 50 on the bed is a short rotatable shaft 93 provided at its inner end with a grooved socket 94 which is shaped to engage a tongued collar 95 on the screw 90 and impart rotary movement thereto. It will be 55 understood that the screw is longitudinally movable with respect to the shaft 93, thus permitting the actuating device and the slide to reciprocate without, however, causing any reciprocation of the screw actuating 60 shaft 93.

65 Feeding is effected by turning the shaft 93, and this is preferably accomplished automatically. Loosely mounted on the shaft is a worm wheel 96 with which meshes a worm 97. Splined to the shaft 93 is a disk

98 and interposed between the disk and the face of the worm wheel is a washer 99 rotatably connected with the worm wheel by means of pins. Springs press the washer outward against the disk, thus providing 70 a frictional connection between the worm wheel and the shaft. The worm 97 is secured to a short horizontal shaft 100 mounted in suitable bearings in a bracket 101 secured to the bed. At one end of the shaft 75 is a bevel gear 102 which meshes with a bevel gear 103 on a horizontal longitudinal shaft 104. The shaft 104 is mounted in bearings secured to or formed integrally with the bed 1 and at the end opposite the 80 bevel gear 103 it is provided with a bevel gear 105 which meshes with a bevel gear 106. The gear 106 is mounted on a transverse horizontal shaft 107 mounted in the bed. To the other end of this shaft there 85 is secured a ratchet wheel 108 and a hand wheel 109. Adjacent the ratchet wheel 108 and loosely mounted on the shaft 107 is a sleeve or bushing 110 provided with an arm 111. Secured to the sleeve 110 is a second 90 arm 112 which carries a spring-pressed pawl 113 normally engaging the ratchet wheel 108.

Pivotedly connected at one end with the arm 111 is a link 114 pivotedly connected at its other end with a lever 115. The lever 95 115 is secured to a transverse shaft 116 mounted in suitable bearings on the bed. At the other end of the shaft 116 is a lever 117 mounted at right angles to the lever 115. Pivotedly connected with the lever 117 100 is an upright link 118 the upper end of which has an adjustable pivotal connection 119 with a bell-crank lever 120 horizontally pivoted to the headstock casting. The pivot 119 can be adjusted toward or away from 105 the pivot of the lever, thus making it possible for the lever as it is rocked to transmit movement to the link 118 to any desired extent. The other arm of the bell-crank lever 120 is provided with a projection 121 which engages a cam member 122 secured to the spindle 7. A coil spring 123 surrounding the shaft 116 tends to rock the shaft and also the bell-crank lever 120 in 110 the direction to hold the projection 121 in engagement with the cam. Thus the cam serves to move the bell-crank and the connected parts in one direction and the spring serves to move them in the other direction.

From the foregoing description it will be 120 seen that as the live spindle is rotated the bell-crank 120 is oscillated and the movement thereof is transmitted to a greater or less extent to the arm 112 and the pawl 113. The movement of the pawl in one direction 125 actuates the ratchet wheel 108, whereas when moving in the other direction the pawl moves freely over the teeth of the wheel. Thus the ratchet wheel is given an intermittent movement, and through the mechanism de- 130

scribed this movement is transmitted to the feed screw 90. The aforesaid movement occurs once for each revolution of the spindle and of the cutter driven thereby and the feed is effected once for each revolution of the cutter. The amount of feed at each revolution can be varied by adjusting the pivot at 119. One of the purposes of the friction elements which have been described 5 is to prevent injury to the machine in case the normal feeding operation is interfered with in any way. In the case of abnormal resistance to feeding, the friction elements will slip and no harm will result.

15 Preferably also there is provided a hand operated means for controlling the tool, this comprising the hand wheel 109 already mentioned. Frequently in order to start the cutting it is desirable to advance the 20 tool in the feeding direction at a speed greater than that caused by the automatic mechanism. This can be done at any time by means of the hand wheel without interfering in any way with the operative relation of the automatic mechanism. The 25 ratchet wheel is advanced with respect to its driving pawl, the teeth of the wheel freely slipping under the pawl. Whenever the more rapid manual movement is discontinued, the movement by means of the pawl is resumed as before.

In order that the tool may be retracted or withdrawn manually, means are provided for interrupting the action of the automatic 30 feeding mechanism, this means preferably comprising a device for holding the pawl 113 out of engagement with the ratchet wheel 108. As shown, this device comprises a lever 124 loosely mounted on the sleeve 110. Secured to this lever is an arcuate 35 finger 125 concentric with the ratchet wheel and positioned adjacent the teeth thereof. As shown in Fig. 1, the finger 125 is positioned out of the path of the pawl, but by 40 moving the finger downward and forward about its pivotal axis the pawl will be held out of engagement with the teeth, thus stopping the feed and leaving the feed mechanism free to be manually moved in either 45 direction. For operating the lever 124 there is provided a link 126 pivotally connected with the lever and provided with a grooved 50 collar 127. As shown in Fig. 7 a hand lever 128 is horizontally pivoted to the bed of the 55 machine, being provided with two forks respectively carrying projections in the form of screws the inner ends of which engage the groove in the collar 127. By moving the hand lever the feed interrupting finger 60 125 can be positioned as required. A spring-pressed pin 129 is provided for holding the lever 128 in either one of its two positions.

For automatic feeding it is preferable to provide means whereby the feeding is automatically stopped at a predetermined limit.

I provide a limiting or stopping device which comprises a button 130 on a T-bolt situated in a T-slot 131 in the disk 98. Co-operating with the button 130 is a movable stop 132 which when in operative position 70 is adapted to be engaged by the button as the disk 98 rotates. By suitably adjusting the button with respect to the disk the button can be made to engage the stop after feeding has taken place to the desired extent. It will be seen that as soon as the button does engage the stop, further movement of the shaft 93 and of the feed screw is prevented, the friction elements permitting the worm to continue to turn as before. 80

When the tool is to be controlled manually, it is desirable to prevent the engagement of the button 130 and the stop 132, and I therefore provide means whereby the stop 132 can be withdrawn. Preferably the 85 stop is withdrawn simultaneously with the movement of the finger 125 to position to interrupt the action of the pawl. In order that this may be done, I provide a short rock shaft 133 on which is mounted a cam 90, 134 which engages the stop 132 and causes it to assume an operative position as shown in Fig. 4 or a lower inoperative position. Also mounted on the shaft 133 is a pinion 135 which is engaged by a rack 136 formed 95 on the end of the aforesaid link 126. With the parts in the positions shown in Fig. 4 the automatic feed mechanism is operative and the stop 132 is in position to limit the amount of feed. When the hand lever 128 100 is moved toward the left the automatic feed mechanism is disconnected and the stop 132 is simultaneously moved to its inoperative position, thus leaving the feed mechanism entirely free for movement manually 105 to the full extent in either direction.

In operation, the operator first observes the number of teeth on the cutter to be relieved and then by placing the lever 25 into proper position and by making use of the 110 proper gears 71, 72 and 74, he provides for the movement of the tool slide as many times per revolution of the spindle as the cutter has teeth. By adjusting the lever 51 by means of the screw 61 the amount of 115 movement of the slide is regulated in accordance with the amount of relief desired on each tooth. By adjusting the pivot bolt 119 in its slot the rate of feed is regulated as required. When the parts have been 120 properly adjusted as outlined above, the tool is brought into working relation with the cutter being advanced manually if necessary. The limit button 130 is so adjusted 125 as to stop the feed after a sufficient cut has been taken.

It is to be observed that by reason of the peculiar mounting of the slide 27 and of the tailstock on the bed independently of each other, the machine is adapted for oper. 130

ation on cutters having a wide range of lengths. It will be obvious that for a relatively long cutter it is possible to move the tool-holder to the same position which is occupied by the tailstock when a shorter cutter is being operated upon.

It will be seen that the action of the machine is entirely automatic after the preliminary adjustments have been made and 10 after the cutter has been put in place, and no harm can result even if the machine does not receive the undivided attention of the operator as the feeding is automatically stopped at the proper time, thus preventing 15 any injury to the cutter.

What I claim is:

1. In a relieving lathe, the combination of a bed, a headstock provided with means for 20 rotating a cutter, a slide mounted on the bed and longitudinally movable therealong, a tailstock mounted directly on the bed and adjustable therealong, the tailstock engaging the bed independently of the slide and at both sides thereof, a tool holder mounted 25 on the slide and adjustable therealong, and means for moving the slide toward and away from the cutter in timed relation to the rotation thereof.

2. In a relieving lathe, the combination of 30 a bed, a headstock provided with means for rotating a cutter, a slide longitudinally movable along the bed, a tool holder mounted on the slide and adjustable therealong, means for moving the slide toward and away from 35 the cutter in timed relation to the rotation thereof, and a tailstock positioned over the slide and directly engaging the bed independently of the slide at both sides thereof, the said tailstock being removable whereby 40 the said tool holder can be moved along the slide to the position normally occupied by the tailstock.

3. In a relieving lathe, the combination of 45 a bed, a headstock provided with means for rotating a cutter, a slide longitudinally movable along the bed, a tool holder mounted on the slide and adjustable therealong, means for moving the slide toward and away from the cutter in timed relation to the rotation 50 thereof, and a tailstock directly engaging the bed over and independently of the slide at both sides thereof and adjustable along the bed, the tailstock being removable whereby the tool holder can be moved along the 55 slide to the position normally occupied by the tailstock.

4. In a relieving lathe, the combination of 60 a bed, a headstock provided with means for rotating a cutter, a slide longitudinally movable along the bed, a tool holder mounted on the slide and adjustable therealong, means for moving the slide toward and away from the cutter in timed relation to the rotation 65 thereof, a tailstock carried by the bed on ways at the sides of the slide, and means

acting at the sides of the tailstock adjacent the ways for locking it to the bed.

5. In a relieving lathe, the combination of a bed, a headstock provided with means for 70 rotating a cutter, a slide longitudinally movable along the bed, a tool holder mounted on the slide and adjustable therealong, means for moving the slide toward and away from the cutter in timed relation to the rotation thereof, a tailstock carried by the bed on ways at the sides of the slide, devices positioned respectively at the sides of the tailstock adjacent the ways for locking it to the bed, and means for operating the said devices simultaneously.

6. In a relieving lathe, the combination of a bed, a headstock provided with means for 80 rotating a cutter, a slide longitudinally movable along the bed, a tool holder mounted on the slide and adjustable therealong, means for moving the slide toward and away from the cutter in timed relation to the rotation thereof, a tailstock carried by the bed on ways at the sides of the slide, devices positioned respectively at the sides of the tailstock adjacent the ways for locking it to the bed, and differential means for operating the said devices.

7. In a relieving lathe, the combination of a bed, a headstock provided with means for 90 rotating a cutter, a slide longitudinally movable along the bed, a tool holder mounted on the slide and adjustable therealong, means for moving the slide toward and away from the cutter in timed relation to the rotation thereof, a tailstock carried by the bed on ways at the sides of the slide, two clamping devices pivoted to the respective sides of the tailstock, and a connecting device for forcing the said devices into engagement respectively with the sides of the bed.

8. In a relieving lathe, the combination of a bed, a headstock provided with means for 100 rotating a cutter, a slide longitudinally movable along the bed, a tool holder mounted on the slide and adjustable therealong, means for moving the slide toward and away from the cutter in timed relation to the rotation thereof, a tailstock carried by the bed on 110 ways at the sides of the slide, two clamping devices pivoted to one of the said devices and extending through the other, and a nut on the rod for moving the said devices toward each other into clamping engagement 115 with the bed.

9. In a relieving lathe, the combination of a bed, a headstock provided with means for 120 rotating a cutter, a tailstock mounted directly on the bed and adjustable therealong, a slide extending under the tailstock and longitudinally movable independently thereof, a tool holder mounted on the slide and adjustable therealong, a slide actuating device mounted independently of the bed and 130

tailstock in ways formed on the bottom of the slide, means engaging the slide and the actuating device for relatively adjusting them; and a reciprocating means directly engaging the actuating device.

10. In a relieving lathe, the combination of means for holding and rotating a cutter, a tool holder, means for moving the tool holder toward and away from the cutter in timed relation to the rotation thereof, a device for giving the tool holder a feeding movement supplemental to the aforesaid normal movements, automatic means comprising a pawl and a ratchet wheel for intermittently operating the feeding device, and a manually controllable device supplemental to the said automatic means for preventing the engagement of the pawl with the ratchet wheel whereby the feeding device is made free for manual movement in either direction.

11. In a relieving lathe, the combination of means for holding and rotating a cutter, a tool holder, means for moving the tool holder toward and away from the cutter in timed relation to the rotation thereof, a device for giving the tool holder a feeding movement supplemental to the aforesaid normal movements, automatic means comprising a pawl and a ratchet wheel and

frictionally engaging elements for operating the feeding device, a device for stopping the feeding device after movement to a predetermined extent, means for disengaging the pawl from the ratchet wheel, and means for rendering the stopping device inoperative whereby the feeding device is made free for manual movement indefinitely in either direction.

12. In a relieving lathe, the combination of means for holding and rotating a cutter, a tool holder, means for moving the tool holder toward and away from the cutter in timed relation to the rotation thereof, a device for giving the tool holder a feeding movement supplemental to the aforesaid normal movements, automatic means comprising a pawl and a ratchet wheel and frictionally engaging elements for operating the feeding device, a device for stopping the feeding device after movement to a predetermined extent, and means for disengaging the pawl from the ratchet wheel and for simultaneously rendering the stopping device inoperative whereby the feeding device is made free for manual movement indefinitely in either direction.

In testimony whereof, I hereto affix my signature.

FRIEDERICH MÜLLER.
